UNITED STATES PATENT OFFICE.

ROY F. RIGGS, OF ALTON, ILLINOIS, ASSIGNOR TO WESTERN CARTRIDGE COMPANY, OF EAST ALTON, ILLINOIS, A CORPORATION OF DELAWARE.

GAME BULLET.

Application filed June 20, 1924. Serial No. 721,198.

To all whom it may concern:

Be it known that I, ROY F. RIGGS, a citizen of the United States, and residing at Alton, county of Madison, State of Illinois, have invented the new and useful Improvement in Game Bullets, of which the following is a specification.

This invention pertains to bullets and more particularly such bullets as are used in high power rifles for hunting game.

In game hunting and particularly in hunting big game, it is desirable to have a bullet which would have a maximum so-called stopping power. The most effective bullet for this purpose is the so-called "mushrooming" bullet which has its tip arranged so as to burst and spread upon impact so as to produce as serious a wound as possible. The ordinary mushrooming bullets have heretofore been constructed of lead or other soft metal in order that they may be more easily deformed upon impact. In some cases soft metal bullets jacketed with a harder metal have been used. With soft metal bullets it has been difficult to produce a body of sufficiently homogeneous material so that the bullet will be properly balanced; that is, unless the material is perfectly homogeneous it is practically impossible to have the center of gravity coincident with the center of form, the center of form being on the axis of the bullet. If the center of gravity is not on that axis, the flight of a bullet is not true. This causes the more difficulty the higher the power of the propelling charge, or in other words, the higher the muzzle velocity with which the bullet is discharged. As the velocity of a bullet has an important bearing on its mushrooming tendencies at impact, it is desirable to provide a bullet which is capable of being given a high velocity and at the same time formed so as to produce the mushrooming effect.

One of the objects of this invention therefore is to provide a game bullet which is not only capable of being discharged at a high velocity and constructed so as to be true in flight, but one which upon impact will spread without breaking so as to provide a maximum stopping power.

Another object is to provide such a bullet

with its tip constructed and arranged to facilitate the mushrooming operation.

Further objects will appear from the following description taken in connection with the accompanying drawing, in which—

Figure 1 is a side view of a bullet embodying this invention.

Figure 2 is a top view of Figure 1.

Figure 3 is a longitudinal section of a bullet embodying this invention; and

Figure 4 is a view somewhat reduced in scale showing the form taken after impact.

In accordance with this invention, the body 1 of the bullet is formed of hard metal such as steel, copper or the like. As a steel bullet presents difficulties in its passage through the rifle barrel, it has been found advantageous to construct the body of copper. The bullet is constructed by cutting from a solid homogeneous piece of material. This may be accomplished by turning the bullet from a drawn copper rod and the body is formed with a tapering tip so as to facilitate its flight through the air. Extending from the tip rearwardly is a bore or cavity 2. This bore terminates short of the base 3 of the body. In fact the bore 2 ordinarily occupies only the forward part of the bullet. In the illustration shown, this bore is flared somewhat toward the tip, but this feature may or may not be desirable according to circumstances. The tapering body meets the central bore 2 so as to provide at the forward end of the bullet a thin wall 4 which is thus weakened so that it is more readily capable of being ruptured and expanded upon impact.

A plug or tip of softer metal may be seated in the forward part of the bore 2 and formed to provide a sharp nose for the bullet. The plug 5 provides a soft metal tip which is the first to strike the object fired at and, receiving the first impact, is deformed and spread so as to assist in rupturing the wall 4 to produce the desired mushrooming effect on the body of the bullet. The bullet may, however, be used without the tip 5 with good effect.

Upon striking the object fired at, the walls 4 are ruptured either by the action of the plug 5 or by the pressure of the air or

animal tissues which may be caught within the bore. Upon rupturing the walls 4, the material is forced outwardly so as to increase the diameter of the bullet and enlarge the wound, and these outwardly bent portions are eventually forced back, as illustrated at 6 in Figure 4.

It will be seen that on account of the form of this bullet and the fact that it is constructed of a homogenous material, the center of gravity thereof will lie in the longitudinal axis or substantially so. This insures that the bullet will have a true flight through the air and will therefore be capable of accurate shooting. This structure also provides that it shall be capable of being given a high velocity so as to strike the object with a maximum force of impact. The hollow bore provides for bursting and mushrooming, and the soft metal plug 5 assists in producing this effect. It is clear therefore that this invention provides a bullet which will have a maximum stopping power.

It is obvious that various changes may be made in the details of construction, without departing from the spirit of this invention; it is therefore to be understood that this invention is not to be limited to the specific details shown and described.

Having thus described the invention, what is claimed is:

1. A game bullet, comprising, a solid body of hard metal provided with axial bore extending rearwardly from the tip thereof and terminating short of the base thereof.

2. A game bullet, comprising, a solid body of hard metal provided with an axial bore in the tip thereof adapted to provide a thin wall adjacent said tip.

3. A game bullet, comprising, a solid body of hard metal provided with an axial bore in the tip thereof, and a soft metal plug in said bore.

4. A game bullet, comprising, a solid body of hard metal provided with an axial bore in the tip thereof, and a soft metal plug having a pointed tip in said bore.

5. A game bullet, comprising a solid cylindrical body of hard metal tapering to a tip and having an axial bore in said tip, and a pointed soft metal plug in said bore.

6. A game bullet, comprising, a partly tapering cylindrical body of hard metal of uniform texture having its center of gravity substantially in the axis thereof, said body having its tip bored coaxially with said body.

7. A game bullet, comprising, a partly tapering cylindrical body of hard metal of uniform texture having its center of gravity substantially in the axis thereof, said body having its tip bored coaxially with said body, and a soft metal plug in said bore.

8. A game bullet comprising a solid hard metal body having a cylindrical rear end and a tapered forward end, said last end having a socket formed therein, to render the forward portion of the body relatively thin and easily susceptible of splitting, and a solid but soft metal slug constituting a tip arranged in the socket and extending beyond the outer end thereof, the outer end of said slug being relatively small and formed with a fine point, for the purpose described.

In testimony whereof I affix my signature this 26th day of May, 1924.

ROY F. RIGGS.
